UNITED STATES PATENT OFFICE.

CHARLES MEYER AND HENRY B. MEADE, OF LOS ANGELES, CALIFORNIA, ASSIGNORS
TO FRANK A. GILLESPIE, OF LOS ANGELES, CALIFORNIA.

AMALGAMATOR.

Original application filed June 2, 1921, Serial No. 474,344. Divided and this application filed October 20, 1921. Serial No. 509,034.

To all whom it may concern:

Be it known that we, CHARLES MEYER and HENRY B. MEADE, citizens of the United States, residing at Los Angeles, in the county of Los Angeles and State of California, have invented new and useful Improvements in Amalgamators, of which the following is a specification.

Our invention relates to an amalgamating apparatus and our present application is a division of our copending application, filed June 2nd, 1921, Serial No. 474,344, and should be read and considered in connection therewith.

The particular objects of our invention are to generally improve upon and simplify the construction of existing types of amalgamators, and to provide relatively simple and efficient means for causing all of the metal carrying material to be brought into direct contact with mercury coated plates, thereby insuring the collection of the relatively finer, or microscopic particles of precious metals; and further to provide an apparatus having a portion that may be readily adjusted so as to control the flow of metal bearing material that passes through the amalgamator.

With the foregoing and other objects in view, our invention consists in certain novel features of construction and arrangement of parts that will be hereinafter more fully described and claimed and illustrated in the accompanying drawings, in which:

Fig. 1 is a top plan view of an amalgamator of our improved construction.

Fig. 2 is a vertical section taken on the line 2—2 of Fig. 1.

Fig. 3 is an enlarged detail section taken on the line 3—3 of Fig. 2.

Referring by numerals to the accompanying drawings which illustrate a practical embodiment of our invention, 10 designates an elongated trough or launder which occupies an inclined position on a suitable supporting frame work 11, and arranged in the upper portion of the higher end of the trough, is a table 12, on top of which is located an amalgam plate 13 which receives the pulp, or material to be treated from a chute or discharge pipe 14.

Positioned within the trough or launder, and leading downwardly therethrough, from the lower end of table 12, is a series of riffles 15 arranged in stepped formation, and

having their upper surfaces covered with plates 16, of suitable material, preferably copper.

Arranged immediately above these stepped riffles, and occupying a plane substantially parallel with the inclined plane occupied by said riffles, is a plate 17, preferably of metal, from the under side of which extends downwardly and forwardly, a series of curved baffle plates 18, of suitable metal, preferably of copper. The number of these plates corresponds with the number of stepped riffles and the lower edge of each curved plate terminates a short distance above one of the plates 16.

The inclined plate 17 is suspended by means of links 19, from a fixed frame 20, which is supported by the side walls of the trough 10, and suitable means is provided for swinging the plate 17 lengthwise so as to move the covered baffle plates toward or away from the riffles. This means comprises a handle 21, the lower end of which is pivotally connected to the central portion of plate 17. The upper portion of said handle carries a transverse pin 22, which is adapted to engage in any one of a series of notches 23 formed in a part of the supporting frame 20.

Arranged in the bottom of the trough 10, below the lower end of the stepped riffles are transversely disposed mercury pockets 24 which communicate on one side of the trough with mercury taps 25.

In the operation of our improved amalgamator, the plates 13, 16, 17 and 18 are all coated with mercury prior to the delivery of pulp or metal bearing material to the trough, and as the pulp is discharged through pipe or chute 14, a certain amount of mercury is mixed therewith so that the metal and mercury carrying pulp after discharging on to plate 13, will, by gravity, flow downwardly over the stepped riffles that are covered with the amalgam plates 16.

As the pulp thus flows downwardly over the riffles, the mercury and the free metal within said pulp, will by reason of its gravity, pass downward on to the amalgam plates 16, so that the free metal will amalgamate with the mercury flowing over said plates. The lighter portion of the pulp, or that portion in the upper strata of the volume, flowing over the riffles, will impinge against the lower portions of the curved baf-

file plates 18, and by the latter, said pulp will be given a whirling motion or turned over, so that any relatively fine or microscopic particles of free metal that are carried in suspension in the latter portion of said pulp, will at some time during its passage downwardly over the step riffles, be brought into contact with one of the mercury coated baffle plates, thereby amalgamating with the mercury. The mercury passes downward through the trough and finally lodges in one of the mercury pockets 24.

In-as-much as the plates 16 and 18 are coated with mercury, practically all of the particles of material in the pulp will at some time during the flow of the pulp between said plates, be brought into contact with a mercury coated surface and as a result, all of the metallic values will be extracted from said pulp and which values amalgamated with the mercury, will pass into the pockets 24, and finally into and through the taps 25, where the mercury bearing the heavier particles of metal will be separated from that of the particles bearing the lighter metal.

By proper manipulation of the handle 21, the plate 17 carrying the curved baffle plates 18, may be swung lengthwise so as to adjust the positions of the baffle plates toward or away from the riffles, and consequently enabling the curved baffle plates to be located so that they will act to the greatest advantage in engaging the upper strata of the pulp flowing downwardly over the riffles.

Thus, it will be seen that we have provided a relatively simple, practical and efficient apparatus for the rapid and economical handling of metal bearing material, and particularly material in pulp form that carries relatively fine or microscopic particles of precious metal.

Obviously, minor changes in the size, form and construction of the various parts of our improved amalgamator may be made and substituted for those herein shown and described without departing from the spirit of our invention, the scope of which is set forth in the appended claims.

We claim as our invention:

1. An amalgamator comprising a series of stepped riffles having amalgamating surfaces, and a series of baffle plates above the riffles, each of said plates being of concave form and associated with the respective riffle to effect a vertical whirling motion of pulp traversing the riffles.

2. An amalgamator comprising a series

of stepped riffles having amalgamating surfaces, a series of baffle plates, one for each of said riffles, each of said plates being of concave form and associated with the respective riffle to effect a vertical whirling motion of pulp traversing the riffles, and means for adjusting all of the riffles simultaneously to vary the whirling motion effected.

3. An amalgamator comprising a series of stepped riffles having amalgamating surfaces, a series of baffle plates, one for each of said riffles, each of said plates being of concave form and associated with the respective riffle to effect a vertical whirling motion of pulp traversing the riffles, means for adjusting all of the riffles simultaneously to vary the whirling motion effected, comprising a frame, a plate carrying the baffle plates and having a link connection with the frame and a lever pivoted to the plate and having an adjustable connection with the frame.

4. An amalgamator comprising a series of stepped riffles having amalgamating surfaces, a series of baffle plates, one for each of said riffles, means for adjusting all of the baffle plates simultaneously to vary the whirling motion effected, comprising a frame, a member to which the baffle plates are fixed and having an operative connection with the frame, and a second member pivoted on the first member and having an adjustable connection with the frame.

5. An amalgamator comprising a series of stepped riffles having amalgamating surfaces, and a series of curved baffle plates above the riffles, each of said plates being associated with the respective riffle to effect a vertical whirling motion of pulp traversing the riffles.

6. An amalgamator comprising a series of stepped riffles having amalgamating surfaces, a series of baffle plates, one for each of said riffles, means for adjusting all of the baffle plates simultaneously to vary the whirling motion effected, comprising a fixed frame, a plate to which the baffle plates are fixed, links for pivotally suspending the plate beneath the frame, said frame being formed with notches, and a lever pivoted to the plate and carrying a pin adapted to engage within the notches for adjusting the lever upon the frame.

In testimony whereof we have signed our names to this specification.

CHARLES MEYER.
HENRY B. MEADE.
